(Cl. D4—3)

FIG. 1

FIG. 2

FIG. 3

FIG. 4

FIG. 5

FIG. 1 is a plan view of a rack for collapsible tubes, embodying my new design.

FIG. 2 is a back elevation thereof.

FIG. 3 is an enlarged fragmentary plan view similar to FIG. 1, the fragment illustrated being typical of the entire length of the rack.

FIG. 4 is an enlarged fragmentary front elevational view thereof.

FIG. 5 is an end view thereof.

The collapsible tubes shown in broken lines in FIGURE 4 are included for illustrative purposes only.

I claim:

The ornamental design for a rack for collapsible tubes, substantially as shown and described.
